IRON HOLDER ATTACHMENT FOR IRONING BOARDS.

Filed Sept. 8, 1927

Attorneys

UNITED STATES PATENT OFFICE

ROMAN F. POLSKI, OF ST. PAUL, MINNESOTA

IRON-HOLDER ATTACHMENT FOR IRONING BOARDS

Application filed September 8, 1927. Serial No. 218,232.

It is the object of this invention to provide a novel and simple attachment for an ironing board adapted to support a hot iron in readily accessible position but removed from the board top upon which the work is placed.

The invention will be best understood by reference to the accompanying drawings in which Figure 1 is a top plan view of my improved attachment removed from the ironing board, Fig. 2 is a section through the same taken on the line 2-2 of Fig. 1, Fig. 3 is a side elevation of the same, Fig. 4 is a fragmentary side elevation of an ironing board of the folding type with my attachment in place thereon and Fig. 5 is an enlarged section taken on the line 5-5 of Fig. 4.

I provide a horizontal support for an iron consisting of a series of parallel, longitudinal members 6 connected at their ends by transverse members 7. This support is preferably constructed from sheet steel or other suitable metal adapted to be stamped in the desired form although it will be obvious that the device may be cast from other suitable metal if desired. A reinforcing rib 8 is formed in each of the members 6 by offsetting the central portion downward. The end members 7 are also reinforced by beads 9 and 10 respectively, which extend entirely across opposite extremities of the support. These beads 9 and 10 project somewhat above the surface of the members 6. Adjacent to the bead 10 is a downwardly projecting flange 11 adapted to be manipulated to retract and extend the support and another flange 12 near the bead 9 prevents complete withdrawal of the support from the board as hereinafter described. Formed upon the outer edges of the side members 6 are upturned flanges 13 adapted to retain an iron, such as the iron 14 indicated in Fig. 4, upon the support.

In Figs. 4 and 5 I have used the numeral 15 to indicate the top of the ironing board to which the attachment is secured. This board 15 has upon its bottom surface near one end a transverse bar or cleat 16 upon the ends of which are swiveled legs 17 and 18 of the folding type adapted to be collapsed upon the bottom of the board. The cleat 16 is se-

cured to the bottom by means of screws 19 and suitable cap screws 20 are provided as pivots for the legs 17 and 18. Extending transverse the member 16 in its upper edge is a series of parallel grooves 21 constituting 55 guide-ways for the members 6 which are slidably held against the bottom surface of the board 15 by the cleat 16.

In securing the iron support on the board the members 6 are placed in the grooves 21 60 before attaching the member 16 and then said member is rigidly secured in place by inserting the screws 19.

When the board 15 is set up ready for use the flange 11 may be grasped to extend the 65 iron support to the position shown in full lines in Fig. 4. Now the iron 14 may be placed upon the grid-like member 6 where it is retained by the bead 10 and the flanges 13. Thus the entire top surface of the board 70 15 is available for supporting the work or material to be ironed. When the board is not in use the members 6 may be retracted beneath the board as indicated in dotted lines in Fig. 4. 75

The bead 9 in addition to forming a reinforcing transverse member of the attachment constitutes a smooth abutment for engagement with the bottom surface of the board 15. As this bead projects above the horizontal surface of the members 6 it tends to raise the outer end of the support when the latter is extended and to firmly retain the members 6 in the grooves 21 by wedging action. Similarly when the attachment is retracted, as 80 indicated in the dotted lines in Fig. 4 the bead 10 has a wedge-like effect against the bottom of the board 15 which retains the support in retracted position until forcibly withdrawn. 85

Having described my invention what I claim as new and desire to protect by Letters Patent is:

In an attachment for an ironing board, a series of parallel, horizontally spaced members, transverse members rigidly connecting said first mentioned members at their ends, a bar secured to the bottom of said board near an end thereof and formed with grooves severally adapted to receive said first mentioned 95 100

member, said bar being arranged to slidably retain said members adjacent to the bottom surface of said board, said members being adapted to be extended from the edge of said board to support an iron and to be retracted beneath the same when not in use.

In testimony whereof, I have hereunto signed my name to this specification.

ROMAN F. POLSKI.
